UNITED STATES PATENT OFFICE.

THOMAS KEPPEL NORTH, OF WESTMINSTER, LONDON, ENGLAND, ASSIGNOR TO
VICKERS LIMITED, OF WESTMINSTER, ENGLAND.

SUBMARINE MINE.

1,309,909.

Specification of Letters Patent.

Patented July 15, 1919.

Application filed June 21, 1917. Serial No. 176,062.

To all whom it may concern:

Be it known that I, THOMAS KEPPEL NORTH, a subject of the King of Great Britain, residing at Vickers House, Broadway, 5 Westminster, in the county of London, England, have invented certain new and useful Improvements in or Relating to Submarine Mines, of which the following is a specification.

10. This invention relates to submarine mines of the kind in which the firing gear comprises a firing arm or lever arranged externally with respect to the mine, this arm or lever, when a ship strikes the mine, moving 15 relatively to the mine against the resistance of a resilient clutch device to effect the firing of the bursting charge.

According to the present invention the said clutch device is disposed co-axially with 20 respect to a longitudinally displaceable firing rod and the clutch element that rotates with the firing arm or lever and carries the said rod, is detachably connected to a part, attached to the mine casing, in such a manner that when a ship strikes the mine the angular movement given to the said clutch element frees it from the said part to permit firing movement of the rod to take place. The said rotary clutch element may itself 25 constitute one member of a species of bayonet joint connection (the other member being constituted by the aforesaid part attached to the mine casing) and may be connected to the anchor cable so that when said 30 clutch element is disengaged from the part attached to the mine casing, the mine will be fired by its upward pull or buoyancy.

In order that the said invention may be clearly understood and readily carried into 40 effect the same will be described more fully with reference to the accompanying drawings, in which:—

Figure 1 is a longitudinal section showing a constructional form of the improved firing gear detached from the mine.

Figs. 2 and 3 are sections taken approximately on the lines 1, 1 and 2, 2 respectively of Fig. 1 and viewed in the direction of the arrows in these figures, and

50. Fig. 4 is a plan of Fig. 1 with the outer casing removed in order to more clearly show the essential features of the improved firing gear.

A (Fig. 1) is the firing arm or lever carried by a member A' that is connected to the

anchor cable of the mine. B is the rod that is detachably connected to the striker head, and C is a collar by means of which the firing gear is attached to the mine casing. D is the rotary clutch element, suitably connected to the member A', E is the non-rotary clutch element, and e is the spring that controls the latter element.

In the example shown the collar C has connected thereto by screw threads or otherwise, a sleeve C' through which and the collar C the rod B passes axially. This rod has a head B' by which connection is established between the clutch element D and the rod so far as axial movement is concerned. 65 The sleeve C' is formed with longitudinal slots c', c' to receive keys c, c that also engage with slots in the collar C, thus preventing relative angular movement from taking place between the sleeve and the collar, and enabling the parts to be readily assembled and dismantled. The said keys are held in position by screws c², c² carried by the collar C. The non-rotary clutch element E has keys e', e' engaging with the said slots c', c'; the 70 spring e for controlling this clutch element, is interposed between the latter and the collar C and surrounds the sleeve C'. The said clutch element is formed on its face with radial projections E', E' of V or other suitable formation and these projections engage in similarly shaped grooves D', D' in the face of the rotary clutch element D. The outer end of the sleeve has two peripheral projections C², C² and the rotary clutch element D has two flanges D², D² which are separated by gaps d², d². The projections C², C² normally occupy the position shown by Fig. 3 and in conjunction with the flanges D², D² and the gaps d², d² constitute a bayonet joint connection between the clutch element D and the sleeve C'. 75 80 85 90 95

The clutch element D is connected to the member A' by means of screw threaded pins a', a' each having a head a² disposed in a recess a³. Between these heads and the ends of the recesses are sal-ammoniac or other soluble plugs a⁴, a⁴. The said member A' has a hollow cylindrical casing or extension A² surrounding the clutch elements D and E, the spring e and the keys c, c and is formed at its end with a slot A³ with which engages one of the screws c², c² serving to hold the keys in their engaged positions. The member A' is thus prevented from ro- 100 105 110

tating until it has been moved axially to disengage the slot A³ from the screw c² after the sal-ammoniac plugs a⁴, a⁴ have been dissolved. A suitable safety pin A⁵ (Fig. 2) is placed between the casing or extension A² and the collar C; this safety pin is sheared when a sudden pull is exerted on the anchor cable connected to the member A', as the mine commences to be drawn beneath the surface of the water by the anchor.

When the clutch element D is displaced angularly as a result of the impact of a ship with the firing arm or lever A, the projections C², C² are brought opposite the gaps d², d²; the clutch element D is thus released from the sleeve C' and the buoyancy of the mine then causes the rod B to be retracted owing to the fact that the head B' connects the rod to the clutch element D which through the member A' is connected to the anchor cable. The striker head then becomes freed from the rod B in any known manner and the mine is thereby exploded.

In order to enable the rotary clutch element D to be readily placed in position in respect to the sleeve C' and the clutch element E, the face of the clutch element D is formed with recesses d, d midway between the grooves D', D' therein; these recesses having sloping surfaces. The clutch element D is placed in a position at right angles to that shown in Fig. 3 with the projections C², C² situated opposite the gaps d², d² and the centers of the recesses d contiguous to the radial projections E', E'. The clutch element D is then pressed inward against the resistance of the spring e and is then angularly displaced to bring the projections C², C² behind the flanges D², D² as shown in Fig. 3. During the first part of this angular movement the radial projections E', E' ride up one or the other of the inclined surfaces of the recesses d and eventually engage with the grooves D', D'. The member A' is then attached to the clutch element D by the screw threaded pins a', a'.

What I claim and desire to secure by Letters Patent of the United States is:

1. In firing gear for submarine mines of the type comprising a buoyant casing for an explosive and an anchor for normally holding the casing submerged, the combination of a socket adapted to be secured to the mine casing, a firing rod displaceable longitudinally relatively to the casing, a clutch device consisting of rotating and non-rotating members disposed co-axially with respect to said rod, a firing arm connected to the rotary member of the clutch device, and means for normally holding said rotary element against rotary movement relative to the mine casing, said means being releasable, so that when a ship strikes the firing arm the angular movement given to said rotary element will free it from the mine casing to

permit movement of the firing rod relative to the mine casing to occur.

2. In firing gear for submarine mines, the combination of a member adapted to be connected to the mine casing, a rotary element, 70 co-operating projections on the member and element forming a bayonet joint, a firing-rod connected to the rotary element so as to be moved lengthwise therewith relative to said member, and a clutch device disposed 75 co-axially with respect to said rod and co-acting with said rotary element.

3. A firing gear for submarine mines comprising the combination of a mine casing, a sleeve depending therefrom, a member co-acting with the sleeve, the sleeve and member having co-operating projections thereon constituting a bayonet lock, a firing-rod connected to the member and extending through the sleeve, a yielding locking device for restraining rotational movement of said member, and a firing arm projecting from the member for turning it relatively to the sleeve to disengage the projections of the bayonet lock. 90

4. A firing gear for submarine mines, comprising the combination of a mine casing, a sleeve depending therefrom, a member coacting with the sleeve, the sleeve and member having co-operating projections 95 thereon constituting a bayonet lock, a firing-rod connected to the member and extending through the sleeve, an annulus on the sleeve, a spring coiled on the sleeve for pressing the annulus into engagement with the member, the sleeve and member having a projection and a co-operating recess therein, and a firing arm projecting from the member for turning it relatively to the sleeve to disengage the projections of the bayonet lock. 100

5. A firing gear for submarine mines, comprising the combination of a mine casing, a sleeve depending therefrom, a member coacting with the sleeve, the sleeve and member having co-operating projections thereon constituting a bayonet lock, a firing-rod connected to the member and extending through the sleeve, an annulus on the sleeve, a spring coiled on the sleeve for pressing the 115 annulus into engagement with the member, the sleeve and member having a projection and a co-operating recess therein, a cylindrical casing rigidly connected to the member and inclosing the annulus and spring, 120 and a firing-arm projecting from the member for turning it relatively to the sleeve to operate the bayonet joint.

6. A firing gear for submarine mines, comprising the combination of a mine casing, a sleeve depending therefrom, a member coacting with the sleeve, the sleeve and member having co-operating projections thereon constituting a bayonet lock, a firing-rod connected to the member and extending 125 130

through the sleeve, an annulus on the sleeve, a spring coiled on the sleeve for pressing the annulus into engagement with the member, the sleeve and member having a projection 5 and a coöperating recess therein, a head secured to the member and movable relatively thereto in the direction of the length of the firing-rod, a soluble member for preventing

such movement, a cylindrical extension on the head inclosing the member, the annulus 10 and the spring, a projection on the mine casting entering a slot in the extension, and a firing arm on the head for turning it and said member.

In testimony whereof I affix my signature. 15
THOMAS KEPPEL NORTH.
